CLAIM

The ornamental design for a receiver and track set, as shown and described.

DESCRIPTION

FIG. 1 is a front perspective view of the receiver and track set, showing my new design, in a disassembled state;

FIG. 2 is a front elevation view thereof;

FIG. 3 is a rear elevation view thereof;

FIG. 4 is a top plan view thereof;

FIG. 5 is a bottom plan view thereof;

FIG. 6 is a right side elevation view thereof, the left side view being a mirror image thereof; and,

FIG. 7 is a front perspective view thereof, showing the receiver and bottom track set of FIG. 1 in an assembled state.

The receiver and bottom track set are shown with symbolic breaks in its length and width. The appearance of any portion of the receiver and bottom track set between the break lines forms no part of the claimed design.
